UNITED STATES PATENT OFFICE.

ADOLF J. WESTMAN, OF MONTREAL, QUEBEC, CANADA.

MAP-DISPLAY DEVICE.

Application filed August 3, 1922. Serial No. 579,345.

To all whom it may concern:

Be it known that ADOLF JULIUS WESTMAN, a citizen of the United States, residing at Montreal, in the District of Montreal and Province of Quebec, Canada, has invented certain new and useful Improvements in Map-Display Devices, of which the following is a specification.

The present invention relates to a display device adapted particularly for maps of web or strip form, and more particularly relates to a device for exhibiting and operating the map particularly during travel.

An object of the present invention is to provide a device of this character which may be readily attached to a motor vehicle in position to be read and operated and adjusted; and a device which interchangeably carries maps which may be quickly and easily inserted and removed from the device and connected to the operating parts thereof.

Another object of the invention is to provide a display device of this character which may be operated in either direction to cause a web or strip to move in the desired direction according to the direction of travel of the vehicle between predetermined points so that the web or map may be exposed and moved continuously or intermittently for uncovering to view consecutive portions of the map and to show direction, distance and condition of roads and the like to the operator of the vehicle.

The invention also aims at the provision of a relatively simply constructed device which may be for the most part stamped and formed from sheet metal and which may be economically and easily assembled into a composite structure, which occupies but relatively small space and which may be mounted upon the windshield or other convenient location upon the vehicle within easy reach of the operator and also within the line of vision.

With the foregoing and other objects in view, the invention will be more fully described hereinafter, and will be more particularly pointed out in the claim appended hereto.

In the drawings, wherein like symbols refer to like or corresponding parts throughout the several views.

Figure 1 is a face view of a display device constructed according to the present in-

vention and having a map strip or web mounted therein.

Figure 2 is a similar view with the cover of the casing and the map strip removed.

Figure 3 is a longitudinal section taken through the complete device substantially on the line 3—3 of Figure 1, and

Figure 4 is an end elevation of the device, showing one type of bracket which may be used for attaching the device upon a motor vehicle.

Referring to the drawing, 10 designates a casing which is relatively shallow and of rectangular form, and which may be constructed of sheet metal or the like. The casing 10 is open at one side and is normally closed by a cover 11 having a marginal flange 12 adapted to overlap the casing 10 and which may be detachably secured thereto in any suitable manner. In the present instance the cover 11 is held to the casing by a projection 13 which is stamped and pressed outwardly from one end of the casing and adapted to engage in an opening 14 formed in the flange 12 of the cover. The other end of the cover is held to the casing by a latch stud 15 carried on a leaf spring 16 which is riveted at 17 to the inner side of the casing 10, the stud 15 projecting outwardly through registering openings formed in the casing 10 and flange 12. The spring 16 may be flexed inwardly by a push button 18 carried by the spring 16 at a point below the flange 12, and which extends outwardly through the casing 10 for easy access, the depression of the button 18 being adapted to retract the stud 15 from the flange 12 and release the cover 11.

The casing 10 is provided with a longitudinally extending filler or bed plate 19 which extends longitudinally within the casing beneath the cover 11 and which has its opposite ends bent downwardly and outwardly to provide walls 20 which are spaced from the opposite ends of the casing to form therewith compartments for spools 21 and 22. The out-turned ends of the walls 20 are secured to the bottom of the casing 10 for firmly holding the plate 19 in position. The cover 11 is provided with a transparent panel 23 of glass or the like which is intermediate the ends of the cover and of sufficient width to fully expose a map strip or web 25 which is adapted to be moved over the plate 19. The spools 21 and 22 carry

the opposite end portions of the web 25 and have axial depressions in one end to receive bearing studs 26 carried upon the free ends of spring arms 27 which are riveted or otherwise substantially secured in one side of the casing 10, the springs 27 being adapted to tension the spools 21 and 22 and hold the same from racing when operated.

The other ends of the spools are supported upon shafts 28 which are mounted for rotation in the opposite side of the casing 10 and which engage in axial openings in the adjacent ends of the spool, and which are connected to the spools for turning the latter by transverse keys or webs 29 carried on the shafts 28 and engaging in kerfs 30 formed in the adjacent ends of the spools. The outer ends of the shafts 28 may be provided with any suitable means for turning the shafts, in the present instance knurled thumb wheels 31 being shown.

The spools 21 and 22 are provided intermediate their ends with transverse slots 32 arranged to receive the ends of the web 25 and by means of which the web may be easily and quickly attached to the spools.

For supporting the casing 10 the latter may be provided with a socket or strap 33 at its under side to receive the shank 34 of a bracket arm 35 which, as shown in Figure 4, may be adjustably clamped upon a second bracket 36 by a bolt or screw 37. The bracket 36 may be given any suitable configuration for attaching it to the part of the motor vehicle upon which the device is to be supported, a bolt or screw 37 may be used for holding the second bracket 35 at the desired angle upon the first bracket to tilt the casing 10 so as to face the operator and to facilitate access to the wheels 31 and the button 18.

It is apparent that the spools 21 and 22 may be driven in any suitable manner, first one spool being operated to wind the web 25 thereon and draw the web across the plate 19 and beneath the transparent panel 25 so that the web may be observed by the operator. If it is desired to reverse the motion of the web 25, the opposite spool is turned to wind the web thereon, the first web being left free to turn under tension of its spring 27 for maintaining the web taut. When it is

desired to remove a spool from the casing it is only necessary to depress the button 18 and swing the cover 11 from the casing and to then retract the adjacent spring arm 27 from the spool which withdraws the bearing 26 and frees the spool. The spool may now be tilted upwardly and removed from the casing together with the web which is wound thereon.

A different web or strip map 25 may then be substituted by reversing the movements and releasing the spring 27 when the spool is in place so as to hold it in the casing ready for use.

It is obvious that various changes and modifications may be made in the details of construction and design of the above specifically described embodiment of this invention without departing from the spirit thereof, such changes and modifications being restricted only by the scope of the following claim.

What is claimed is:

A display device for maps and the like comprising a casing having an open top, a bed plate in the casing adjacent the top thereof and having its ends bent inwardly and flaring towards the ends of the casing providing pockets in the opposite ends of the casing, springs mounted in one side of the casing and extending oppositely into the adjacent ends of said pockets, bearing studs carried upon the free ends of the spring, spools seated in the pockets having axial openings in opposite ends, each spool having one end engaging a bearing stud, said spools adapted to carry the ends of a map strip for passage over said bed plate, operating shafts arranged in the other side of the casing for engagement in the openings in the other ends of the spools and provided with transverse webs, said spools having kerfs in said other ends adapted to receive said webs for interlocking the spools and operating shafts together, and a removable cover for the open top of the casing having a transparent panel adapted to overlie said bed plate and expose the section of map passing thereover.

In testimony whereof I affix my signature.

ADOLF J. WESTMAN.
